(57) **CLAIM**

The ornamental design for an eyebrow spoolie and spatula tool, as shown and described.

DESCRIPTION

FIG. 1 is a perspective upright view of a first embodiment of my eyebrow spoolie and spatula tool.

FIG. 2 is a front view of the eyebrow spoolie and spatula tool shown in FIG. 1.

FIG. 3 is a back view of the eyebrow spoolie and spatula tool shown in FIG. 1.

FIG. 4 is a view from the right of the eyebrow spoolie and spatula tool shown in FIG. 1.

FIG. 5 is a view from the left of the eyebrow spoolie and spatula tool shown in FIG. 1.

FIG. 6 is an enlarged top end view of the eyebrow spoolie and spatula tool shown in FIG. 1.

FIG. 7 is an enlarged bottom end view of the eyebrow spoolie and spatula tool shown in FIG. 1.

FIG. 8 is a perspective upright view of a second embodiment of my eyebrow spoolie and spatula tool.

FIG. 9 is a front view of the eyebrow spoolie and spatula tool shown in FIG. 8.

FIG. 10 is a back view of the eyebrow spoolie and spatula tool shown in FIG. 8.

FIG. 11 is a view from the right of the eyebrow spoolie and spatula tool shown in FIG. 8.

FIG. 12 is a view from the left of the eyebrow spoolie and spatula tool shown in FIG. 8.

FIG. 13 is an enlarged top end view of the eyebrow spoolie and spatula tool shown in FIG. 8; and,

FIG. 14 is an enlarged bottom end view of the eyebrow spoolie and spatula tool shown in FIG. 8.

Portions of the embodiments of my eyebrow spoolie and spatula tool shown in FIGS. 1-14 shown in dashed lines form no part of the claimed invention.
